Fig. 4

To all whom it may concern:

Be it known that I, Walter Baker, Jr., a citizen of the United States, residing at Louisville, State of Kentucky, have invented a new, original, and ornamental Design for a Bidet, of which the following is a specification, reference being had to the accompanying drawing, forming a part hereof.

Figure 1 is a view in perspective showing the front, top, and one side of my design for a bidet.

Figure 2 is a view in rear elevation of the bidet shown in Figure 1.

Figure 3 is a plan view of the bidet shown in the other figures, and

Figure 4 is a view in side elevation of the bidet shown in the other figures.

The dominant features are shown in full lines.

I claim:

A new and ornamental design for a bidet, substantially as shown and described.
